[57] CLAIM

The ornamental design for a combination backpack and game carrier, as shown and described.

DESCRIPTION

FIG. 1 is a perspective view of a combination backpack and game carrier showing my new design; The broken line showing of another backpack is for illustrative purpose only and forms no part of the claim;

FIG. 2 is a front elevational view thereof;

FIG. 3 is a rear elevational view thereof;

FIG. 4 is a right end elevational view thereof;

FIG. 5 is a left end elevational view thereof;

FIG. 6 is a top plan view thereof; and,

FIG. 7 is a bottom plan view thereof.
